UNITED STATES PATENT OFFICE

167,000

RECEPTACLE FOR ASHES, EGGS, PINS AND THE LIKE

Floyd Everett Rogers, New Westminster,
British Columbia, Canada

Application January 8, 1951, Serial No. 13,711

Term of patent 3½ years

(Cl. D85—2)

To all whom it may concern:

Be it known that I, Floyd Everett Rogers, a citizen of Canada, residing at New Westminster, British Columbia, Canada, have invented a new, original, and ornamental Design for Receptacle for Ashes, Eggs, Pins, and the like, of which the following is a specification, reference being had to the accompanying drawing, forming part hereof.

Figure 1 is a perspective view of a receptacle for ashes, eggs, pins, and the like, showing my new design.

Figure 2 is a side elevation, and
Figure 3 is a top plan view.

I claim:

The ornamental design for a receptacle for ashes, eggs, pins, and the like, as shown.

FLOYD EVERETT ROGERS.
